(57) **CLAIM**

The ornamental design for seating furniture, as shown and described.

DESCRIPTION

FIG. 1 is an isometric view of a first embodiment of seating furniture, in the form of a chair, incorporating my new design;

FIG. 2 is a front elevation view thereof;

FIG. 3 is a side elevation view thereof;

FIG. 4 is a top plan view thereof;

FIG. 5 is a rear elevation view thereof;

FIG. 6 is an isometric view showing another embodiment of seating furniture, in the form of a love seat, incorporating my new design;

FIG. 7 is a front elevation view thereof;

FIG. 8 is a side elevation view thereof;

FIG. 9 is a top plan view thereof;

FIG. 10 is a rear elevation view thereof;

FIG. 11 is an isometric view of another embodiment of seating furniture, in the form of a chair, incorporating my new design, wherein the side elevation is the same as FIG. 3;

FIG. 12 is a front elevation view thereof;

FIG. 13 is a top plan view thereof;

FIG. 14 is a front elevation view thereof;

FIG. 15 is an isometric view of another embodiment of seating furniture, in the form of a chair, incorporating my new design, wherein the side elevation is the same as FIG. 3;

FIG. 16 is a front elevation view thereof;

FIG. 17 is a top plan view thereof; and,

FIG. 18 is a rear elevation view thereof.
